FIG. 3.

UNITED STATES PATENT OFFICE.

HOWARD F. SNYDER, OF NEWTON, IOWA, ASSIGNOR TO THE MAYTAG COMPANY, OF NEWTON, IOWA, A CORPORATION OF IOWA.

WASHING-MACHINE.

1,381,941.

Specification of Letters Patent. Patented June 21, 1921.

Application filed October 6, 1915. Serial No. 54,351.

To all whom it may concern:

Be it known that I, HOWARD F. SNYDER, a citizen of the United States, residing at Newton, in the county of Jasper and State 5 of Iowa, have invented certain new and useful Improvements in Washing-Machines, of which the following is the specification.

This invention relates to washing machines and particularly to a compact, convenient, simply arranged power plant for 10 performing washing, including driving devices, gearing, a washing machine and a platform to accommodate an extra tub.

It is an object of the invention to provide 15 a washing machine of light, simple, compact construction in which all of the gears are well protected.

It is another object of this invention to provide a washing machine having a concealed driving gearing including a reverse 20 for a wringer.

It is another object of the invention to provide a washing machine having driving mechanism located underneath the tub and 25 in combination with a dolly mechanism projecting upwardly from the bottom thereof.

It is another object of the invention to provide a swinging wringer support combined with the other features above enumerated 30 in a new and desirable fashion. Other objects and advantages of the invention will appear as the description to follow proceeds:

35 Figure 1 is a perspective view of the complete washing machine.

Fig. 2 is an end elevation thereof partly in section.

Fig. 3 is a horizontal sectional view of the 40 machine showing the driving connections.

Fig. 4 is a detailed cross-sectional view of the gear box in the wringer support.

Fig. 5 is a detailed cross-sectional view of the reversing gear.

45 In the drawings, 1 represents generally a stand constructed of angle irons and metal plates and having legs 2 provided with casters 3 whereby the entire machine may be easily rolled about from place to place.

50 Rigidly secured to the stand 1 as by means of the interval brackets 4 is a corrugated metallic tub 5; preferably made of aluminum and having a dome shaped top 6 and a constricted bottom 7 as shown in the drawings.

55 The tub 5 is situated adjacent one end of

the stand leaving a platform 8 for the reception of a tub, clothes basket or other container.

The main shaft 9 of the machine is mounted at one end in a bearing 10 secured to one leg of the stand and at the other end in one of the five bearings 10' forming a part of a casting 11. The casting 11 comprises a bracket secured to one side at one end of the stand and is provided with a vertical bearing 12 for the accommodation of the wringer shaft 13. Bolted to the casting 11 is a casing 14 for a crown gear. Loosely mounted upon the main shaft 9, and interposed between the bearings 10' upon the 60 casting 11, are beveled pinions 15 in mesh with the crown gear 16 firmly mounted upon the shaft 13. Between the beveled pinions 15, and splined to the shaft 9 is a clutch 17 which may be shifted to engage either beveled pinion or into neutral position as shown in Fig. 5. The shifting means comprises a fork 18 mounted upon a rock shaft 19, mounted in bearings 20 in the stand extending across the stand and being provided at its end opposite from the shaft 13 with an operating handle 21 which is provided with a rib 22 to engage one of the notches upon a plate 23 secured to the stand, thus setting the clutch 17 in either of the 70 three positions above described. A spring 23' serves to hold the handle 21 in adjusted position. The shaft 13 projects upwardly adjacent the tub 5 and has bearings in a bracket 24 secured to the tub, which bracket 75 at its lower end 25 is integral with the bearing 12 for the shaft 13, and at its upper end is provided with another bearing 26 for the same shaft. Rigidly secured to the tub is a cup shaped member 27 having a bearing 80 at its center for the shaft 13 and being provided with a plurality of notches 28. Rotatively mounted in this cup shaped bearing 85 is the circular bottom of a gear box 29 which is provided with a depending leg 30 having 90 at its bottom a collar 31 resting upon the bearing 12. The shaft 13 projects upwardly through the gear box 29 and is provided therein with a loose gear 32 and with a clutch 33 operated by a fork 34, mounted upon a rock shaft 35 in turn operated by the handle 36 outside the gear box. Secured to the gear box by bolts such as 37 is a wringer 95 comprising lower arms 38; upper arms 39 in which the lower and upper rolls 40 and

75

80

85

95

100

41 are mounted and having integrally formed casings 42 and 43 for the lower and upper rolls and an instantaneous releasing mechanism comprising T-head bolts 44, 5 passing through the lower arms 38 and adapted to draw down the upper roll by means of springs 45, which bolts when turned, come into register at their heads with openings in the upper arms to instantaneously release the wringer rolls without changing the tension of the springs. The handle 50 and crank and link construction 50' serve to turn both bolts simultaneously. The construction of the wringer thus described is the subject-matter of a copending application in which it is set out in more detail.

Slidably mounted in depending extensions 51 from the ringer casing is a rod 52 which is urged inwardly by a spring 53 bearing at one end against a pin 54 through the rod and at its other end against one of the depending lugs 51. The rod 52 is provided with a handle 55; at its inner end it is adapted to engage in one of the openings 28. From this construction, it will be immediately seen that by pulling the rod 52 outwardly, the gear box and wringer thereon may be swung about the vertical shaft 13 and locked in an adjusted position by the engagement of the rod 52 in one of the notches 28. The lower wringer roll shaft projects through the gear box 29 and is provided with a gear 32' in mesh with the gear 32.

The washing machine shown is provided with a dolly which projects upwardly from the bottom of the tub, the precise construction of the dolly and its operating mechanism being the subject-matter of a co-pending application. It is sufficient to say here that the dolly shaft 60 is provided with a gear 61 which is oscillated by engagement with a rack 62 having flanges 63 which embrace the gear 61 and which is held to its work by the rest 61' depending from the bottom of the tub. The rack 62 is made integral with a link 65 which is pivotally connected at its outer end with a pin 66 projecting through the crown gear 16.

The motor 70 rests against and upon the angle iron 71 secured to cross bars 72 at either end of the stand and is equipped with a forwardly and downwardly extending frame comprising side pieces 73, having split bearings 74 upon the shaft 9. The main shaft 75 of the motor projects outwardly between the side pieces 73 and is provided with a worm which drives the spiral gear 76 loose on shaft 9. The gear 76 is located between two friction faces 78, one of which (not shown) is mounted on the spider 79 keyed to the shaft 9, and the other of which is forced against the opposite side of gear 76 by spring 80 which rests at its

other end against collar 81 also pinned to the shaft 9.

By this construction a frictional slip drive is provided which permits the washing machine to come to rest should something stick 70 in the tub and obstruction occur, and prevent breaking or straining the machine.

I claim:

1. In apparatus of the class described, a stand, a support thereon, a vertical oscillatory shaft in said support, a horizontal driving shaft, a vertical driven shaft having a gear thereon, a pinion on said driving shaft for driving said gear, a crank on said gear, connections between said crank and said vertical oscillatory shaft for driving the same.

2. In apparatus of the class described, a stand, a support thereon, a vertical oscillatory shaft in said support, means for oscillating said oscillatory shaft, a horizontal driving shaft, a vertical driven shaft, connections including a revolute clutch between said horizontal shaft and said vertical drive shaft, said connections also including means for operating said oscillating means.

3. In apparatus of the class described, a stand, a support thereon, a vertical oscillatory shaft in said support, means for operating said oscillatory shaft, a horizontal shaft mounted in said stand, a vertical driven shaft, driving connections including a reversing clutch between said horizontal shaft and said vertical shaft, means for shifting said clutch longitudinally to manipulate said driving connections, said driving connections also including means for operating said oscillating means.

4. In apparatus of the class described, a stand, a support thereon, a vertical oscillatory shaft in said support, a horizontal driving shaft, a vertical driven shaft, driving connection between said horizontal shaft and said vertical driven shaft, said connection also including means to operate said oscillatory shaft.

5. In apparatus of the class described, a stand, a support thereon, a vertical oscillatory shaft in said support, a horizontal driving shaft, a vertical driven shaft, driving connection between said horizontal shaft and said vertical driven shaft, said connection also including means to operate said oscillatory shaft, a prime mover, and slip connections between said prime mover and said horizontal shaft whereby if one becomes locked the other may continue to rotate for a short interval.

In witness whereof, I hereunto subscribe my name to this specification in the presence of two witnesses.

HOWARD F. SNYDER.
